MUFFLER

William B. McLeod, Burbank, Calif.

Application November 24, 1951, Serial No. 258,010

1 Claim. (Cl. 181—57)

1

This invention relates to improvements in mufflers for muffling or silencing the exhaust from internal combustion engines.

A primary object of the invention is to provide an improved muffler which is extremely simple in design, enabling the parts to be easily manufactured and assembled and which is highly efficient in its operation, providing for adequate expansion of gases and a ready heat-transference to the ambient atmosphere.

With the foregoing and other objects in view, which will be made manifest in the following detailed description and specifically pointed out in the appended claims, reference is had to the accompanying drawings for an illustrative embodiment of the invention, wherein:

Figure 1 is a longitudinal horizontal section through one form of muffler embodying the present invention;

Fig. 2 is a vertical section taken substantially upon the line 2—2 upon Fig. 1;

Fig. 3 is a vertical section through another form of muffler embodying the present invention;

Fig. 4 is a vertical section taken substantially upon the line 4—4 upon Fig. 3 in the direction indicated;

Fig. 5 is a longitudinal section through still another form of muffler embodying the present invention; and

Fig. 6 is a vertical section taken substantially upon the line 6—6 upon Fig. 5 in the direction indicated.

Referring to the accompanying drawings wherein similar reference characters designate similar parts throughout, 10 indicates an inlet pipe adapted to be connected to the exhaust pipe from an internal combustion engine. This pipe extends into a shell or outer housing through an end plate 11 thereof. The outlet or tail pipe from the muffler is indicated at 12 which extends outwardly through an end plate 13. The end plates 11 and 13 may be welded to the pipes 10 and 12, respectively. They are connected to each other by an outer shell of sheet metal indicated at 14, the end edges of which may be welded or crimped onto the end plates as indicated at 15.

Within the outer housing the portions of the pipes 10 and 11 are perforated with perforations indicated at 16 and 17, respectively, and in the preferred form of construction the diameter of the inlet pipe 10 is slightly larger than that of the outlet or tail pipe 12 although this relative size is not usually important insofar as the present invention is concerned. The two pipes 10

and 12 in the construction shown in Fig. 1 are coaxially arranged and are in direct alignment with each other. Their inner ends, however, are spaced from each other and are surrounded by a sleeve 18 having an internal diameter somewhat larger than the external diameters of the pipes 10 and 12. This sleeve is divided centrally by means of transverse imperforate partition 19. The end edges of the sleeve are divided or slotted to define fingers 20 that can be bent inwardly to frictionally engage the inner ends of the pipes 10 and 12. This frictional engagement in some forms of muffler may be sufficient to hold the sleeve 18 in position. However, in other instances it may be desirable to weld the ends of the fingers to their respective pipes.

In this form of construction as the exhaust gases from the internal combustion engine enter the pipe 10 some of these gases may expand or find egress through the perforations 16. A substantial portion and probably a major portion of the gases issue from the inner end of the pipe and encounter the imperforate partition 19. These gases flow between the interior of the sleeve 18 and the exterior of the pipe 10 between the fingers 20 and enter the space 21 within the outer housing which forms a relatively large expansion chamber in which the gases can expand and heat may be transferred through the sheet metal shell 14 to the surrounding atmosphere. The expanded and cooled gases reenter the sleeve 18 between the sleeve and the outlet pipe 12, such gases flowing between the fingers 20. Some of the gases may enter the pipe 12 through the perforations 17 and thus pass out of the muffler.

It will be appreciated from the above-described construction that the parts of the improved muffler may be very easily manufactured and assembled together and provision is made for releasing the gases into a relatively large expansion chamber near the forward end of the muffler and ultimately conducting these expanded gases to the tail pipe.

The construction disclosed in Fig. 1 may be advantageously employed where the inlet pipe and the outlet pipe 12 can be in direct alignment. In some muffler constructions, however, it is necessary that the inlet pipe and the tail pipe bear an offset relation to each other. Fig. 3 discloses such a construction wherein the inlet pipe is indicated at 25 extending into the outer housing through an end plate 26. In a similar manner, the outlet pipe 27 leads out of the muffler through an end plate 28. The two pipes 25 and 27 bear an offset relationship to each other al-

though they are parallel. In this construction, the inner end of the inlet pipe 25 is surrounded by a sleeve 29 in spaced relation to the exterior of the inlet pipe. Fingers 30 may be utilized to hold the sleeve in spaced relation thereto. The sleeve is closed at its remote end by an imperforate wall 31 corresponding in position and in function to the partition 19. In a similar manner, the inner end of the outlet pipe 27 is provided with a sleeve 32 closed at its inner end by an imperforate wall 33 and having fingers 34. The two pipes 25 and 27 may be perforated with perforations 35 and 36 within the outer housing that is defined by the shell 37 that connects the end plates. The exteriors of the two sleeves 29 and 32 may be rigidly connected together, such as by straps 38 welded thereto. In this form of construction, exhaust gases entering the inlet pipe 25 may find egress therefrom through the perforations 35 and after encountering the wall 31 they are caused to flow in a reverse direction between the sleeve 29 and the inlet pipe and between the fingers 30. These gases may expand within the outer housing and lose a substantial portion of their heat through the walls of the outer housing. The expanded gases enter the tail pipe 27 through the perforations 36 and by flowing between the sleeve 32 and the inner end of the tail pipe. This form of construction functions in very much the same manner as that previously described, but is so designed that an offset inlet and outlet pipe may be employed where such a construction is required.

In a construction, as shown in Figs. 5 and 6, the inlet pipe is illustrated at 40 and the outlet pipe at 41. These pipes are perforated with perforations 42 and 43 and are arranged in alignment with each other. A sleeve 44 surrounds the adjacent ends of the two pipes and is divided by an imperforate partition 45. This sleeve may be held in concentric relationship with respect to the pipes by means of the fingers 46. However, in this form of construction which has been designed for heavy duty, plates 47 and 48 are telescoped over the inlet pipe 40 and secured thereto such as by welding. A similar plate 49 may be telescoped over the outlet pipe 41. Angle irons 50 are positioned against the corners of these plates and are welded thereto. These angle irons extend from end to end of the outer housing 51 and have their ends secured to the end plates thereof. The central portions of the angle irons are arranged to be in engagement

5 with the sleeve 44 and are welded thereto. In this manner, the angle irons extending from end to end of the outer housing cooperate to sturdily support the sleeve 44 centrally of the housing and in concentric relationship to the inner ends of the two pipes 40 and 41. They also cooperate through the plates 47, 48, and 49 to firmly support the pipes 40 and 41 within the outer housing. The operation of the form of construction disclosed in Figs. 5 and 6 is substantially the same as that previously described.

10 From the above-described construction it will be appreciated that the improved muffler can be easily and economically manufactured and have its parts readily assembled together. In operation, gases discharged into the muffler are given an opportunity to expand in a relatively large expansion chamber and are ultimately collected and directed into the tail pipe.

15 20 Various changes may be made in the details of construction without departing from the spirit and scope of the invention as defined by the appended claim.

I claim:

25 A muffler comprising an outer elongated housing, end plates having openings therein covering each end of the housing, aligned inlet and outlet pipes extending into the housing through the openings in said end plates, the interior ends 30 of said pipes being in a spaced-apart relationship, a sleeve about the inner adjacent ends of said pipes, a partition in said sleeve between the inner ends of said pipes, elongated angle irons 35 within said housing and secured to said sleeve, a number of plates telescoped onto the pipes and secured to said angle irons, said angle irons being supported within said housing by said end plates.
